Application August 21, 1931, Serial No. 558,584,
 and in Germany September 8, 1930

10 Claims. (Cl. 112—197)

The invention relates to new and useful improvements in sewing machines, and more particularly to a sewing machine for forming single chain stitches.

5 An object of the invention is to provide a machine of the above character having a non-thread carrying looper moving into and out of the needle thread loops to aid in en chaining the needle thread loops, wherein said looper is so operated as to positively place the needle thread loop about the needle, independent of any action of the feed of the material, so that the material may be fed in any direction during stitching.

A further object of the invention is to provide 15 a sewing machine of the above type wherein the looper is oscillated for movement into and out of the needle thread loop, and is given a bodily rotation about the axis of the needle for positively placing the needle thread loop carried by the looper around the needle adjacent the point thereof.

A further object of the invention is to provide 25 a machine of the above type with means for reciprocating the needle and giving a dwell there- to while the looper is rotated for the placing of the needle thread loop carried by the looper around the needle.

A still further object of the invention is to provide 30 means for automatically lifting the presser foot so as to permit the manual movement of the fabric in any direction during the stitching operation.

In the drawings—

Figure 1 is a view partly in front elevation and 35 partly in section showing the machine embodying the improvements;

Fig. 2 is a view partly in plan and partly in horizontal section through the work arm;

Fig. 3 is a detail in horizontal section at the 40 end of the work arm and showing the mounting of the looper;

Fig. 4 is a view partly in plan and partly in horizontal section through a portion of the over- 45 hanging arm showing the needle actuating mechanism and the presser foot lifting mechanism;

Fig. 5 is an end view of the machine with the cover plate for the needle head removed;

Fig. 6 is an enlarged sectional view lengthwise 50 of the work arm at the free end thereof showing the looper at the rear end of its stroke and the needle at the lower end of its reciprocation;

Fig. 7 is a view showing the looper moved forward to enter the needle thread loop and the needle partly retracted. The looper is also

shown in broken lines all the way to the forward end of its stroke.

Fig. 8 is a view showing the needle above the fabric and the looper as having been rotated bodily through an arc of 180 degrees;

Fig. 9 is a view similar to Fig. 8, but showing the looper as having rotated through an arc of 360 degrees;

Fig. 10 is a view similar to Fig. 9, omitting the 65 en chained thread loops and the twist in the needle thread loop, and also the needle thread as it passes through the needle for the sake of clear- ness, and with the needle moved downward so that its point is just below the upper edge of the looper;

Fig. 11 is a view similar to Fig. 10, but showing the looper as having turned or rotated in a reverse direction from its first rotation through an arc of 180 degrees;

Fig. 12 is a view similar to Fig. 11, but showing 70 the looper as having rotated in a reverse direc- tion through 360 degrees, and as having returned to its normal position for oscillation, and

Fig. 13 is a view similar to Fig. 12, but showing the needle as having passed down so that the 80 point is substantially at the lower edge of the looper.

The invention is directed to a sewing machine which is particularly adapted for the closing of holes in bags and the like. The stitch forming 85 mechanism includes a needle and a non-thread carrying looper which cooperates therewith in forming the single thread chain stitches. The material which is being sewed is fed in different directions back and forth and transversely so 90 as to join the needle threads to the fabric and completely close the hole therethrough by the en chained thread loops. The machine includes a reciprocating needle and a non-thread carrying looper which is mounted for oscillation and also 95 for rotation. The looper is moved into the needle thread loop and holds the needle thread loop so that the needle on its next descent, will enter the loop of needle thread carried by the looper. The looper, when in the needle thread loop, is ro- 100 tated so that the looper is carried bodily around the longitudinal axis of the needle. It is rotated first in one direction through an arc of 360 de- grees, which gives a twist to the needle thread loop, and then it is rotated in the reverse direc- 105 tion. During this time, the needle is so positioned that the movements of the looper will wrap the strand of the needle loop around the needle. The looper is oscillated by a rock lever which in turn is oscillated by a rotating cam.

The needle is reciprocated by a needle lever which in turn is actuated by a rotating cam. The looper is rotated by a segment gear which in turn is reciprocated by an actuating lever oscillated by 5 a rotating cam.

The invention will be better understood by a detail description of the illustrated embodiment of the invention. The machine includes a standard 1 carrying a work supporting arm 2, which 10 as shown, is of the general cylindrical type. Carried by the standard 1 is an overhanging arm 3 carrying a needle head 4. Mounted for reciprocation in the needle head is a needle bar 5 carrying a needle 6. The needle lever 7 pivoted at 8 is 15 connected by a link 9 to the needle bar for reciprocating the same. This lever 7 carries a roller 10 which runs in a cam groove formed in a disk 11 carried by the main shaft 12. This shaft 12 is mounted in suitable bearings in the standard 1.

The fabric to be stitched is supported on the work supporting member or throat plate 13 and is held thereon by a presser foot 14 carried by a presser bar 15. This presser bar is mounted in 20 the needle head and is yieldingly urged against the work support by any suitable means. Mounted on the presser bar is a collar 16 carrying a forked arm 17 which straddles the needle bar 5. A collar 18 carrying a lug to which the link 9 is 25 attached, on the upward movements of the needle bar engages the forked arm 17 and raises the presser foot from the material. This occurs when the needle is reaching the upper end of its stroke and releases the fabric from the pressure of the 30 presser foot so that it may be readily shifted to any desired distance by the operator, and in any direction. This enables the enchain thread loops to be laid back and forth and crosswise until the hole in the fabric is completely filled by the 35 enchain thread loops.

Cooperating with the needle beneath the work support is the looper 19. This looper 19 is in the form of a pointed blade, the under face of which is substantially straight, and the upper face of 40 which is curved. The looper is carried by a shank 20 mounted in a carrier 21 and secured therein by a set screw 22. The carrier 21 is attached to a shaft 23 passing through lugs 24, 24 formed as a part of a support 25. The looper is free to oscillate on this support. Said looper is oscillated by means of a rod 26 which is connected to a lever 27 at 28. The lever 27 is mounted on a cross shaft 29 for free movement thereon, and carries a roller 30 at its upper end running in a cam groove 31 in a disk 32 on the main shaft 12. The rod 26 carries a head 33 which engages a ball 34 in the shank 20 of the looper. This is for the purpose of 45 permitting the looper to rotate in the head. The rod 26 has a threaded engagement with the head 33 and also with the part connected to the lever 27, and these threads are right and left-hand threads, so that by turning the rod, the working position of the looper may be varied. The rod 26 is guided in its endwise movements by a guide plate 35 secured by screws 36, 36 to a vertical web carried by the work arm 2. The rod passes 50 through an opening in this vertical web and through the forked end of the guide plate 35. This prevents any sidewise or lateral movements 55 of the rod.

The support 25 for the looper is cone-shaped on its under face and is mounted in a cone-shaped bearing in the work arm. A shaft 37 is attached to this support 25 and carries a sleeve 70 having a cone 38 at its lower end mounted in a

plate 39 which is attached to the work arm. This sleeve is keyed to the shaft so that when the sleeve is rotated it will rotate the support 25. The sleeve is provided with a gear 40 which meshes with a gear 41 on a sleeve 42. The sleeve 80 42 carries a second gear or pinion 43 which meshes with a segment rack 44 carried by an arm 45 attached to a shaft 46. The shaft 46 is mounted in suitable bearings in the work arm and in the plate 39. This shaft 46 carries an arm 47 which is attached to a rod 48. The rod 48 is in turn attached to a lever 49 mounted freely in the cross shaft 29, and the lever 49 at its upper end carries a roller running in a cam groove in a disk 50 on the actuating shaft 12. When this segment gear 44 is oscillated, it will impart through the gear with which it meshes, and the connecting gears operated thereby, a rotation to the support 25. The cams for reciprocating the looper and for rotating the same, are so timed that the looper moves forward into the needle thread loop to the forward end of its stroke, after which the looper is rotated through an arc of 360 degrees, and then it is returned by a reverse rotation through an arc of 360 degrees, 90 after which the looper is retracted from the needle thread loop. The looper moves alongside of the needle in order to enter the needle thread loop, and therefore, during its rotation, it will be caused to move bodily around a vertical line containing the path of reciprocation of the needle. This path of reciprocation of the needle is substantially in alinement with the axis of rotation of the support 25.

Between the plate 39 and the lower member of 100 the work arm there is a chamber in which is placed the segment rack, and the pinions or gears for rotating the looper. This chamber is substantially closed, and will serve as a lubricating well or chamber for the parts disposed therein.

The operation of the stitch forming mechanism is best illustrated in Figures 6 to 13. In Figure 6, the needle is at the lower end of its stroke, and has formed a needle thread loop into which the looper enters as it moves forward. At this time, 110 the looper is not being rotated. In Figure 7, the looper is shown in full lines part way into the needle thread loop, and in broken lines all the way into the needle thread loop. The needle in Figure 7, is shown as moving upward. In Figure 120 8, the needle has been withdrawn from the fabric and is still on its up-stroke. During this time the looper is rotated through 180 degrees, and while it is rotated, it is not moved from its forward position through the oscillating means 125 therefor. The looper continues its rotation until it reaches the position shown in Figure 9. The looper has been turned through an arc of 360 degrees. The needle thread is indicated at *n*. The needle thread loop on the looper is indicated at *n'*. This rotation of the looper twisted together the strands of the needle thread loop as indicated at *n²* (Fig. 9). In Figure 10, the twisted strands have been omitted for the sake of clearness. This figure, however, shows the looper in 130 the position as shown in Figure 9, but with the needle having moved down until its point is just below the upper edge of the looper. The needle at this time comes to a dwell, or substantially to a dwell, and remains at a dwell while the looper 140 is being rotated in a reverse direction through an arc of 360 degrees. This dwell in the movement of the needle is given through the shaping of the cam which reciprocates the needle bar. When the parts are positioned as shown in Fig- 150

ure 10, the needle, as viewed, is in front of the blade of the looper. The strand n^3 of the needle loop is in front of the blade, while the strand n^4 is in rear of the blade of the looper, and consequently in rear of the needle. As the looper is turned through the reverse rotation 360 degrees, or to the position shown in Figure 11, then the blade of the looper is moved to the other side, or in front of the needle point, as viewed in this figure. This movement of the looper positively carried the strand n^4 of the needle loop part-way around the needle at the portion thereof between the eye of the needle and the point of the needle. The continued reverse rotation of the looper to the position shown in Figure 12 will positively carry this strand n^4 from about the needle and bring the blade of the looper to the rear or opposite side of the needle from that as viewed in Figure 11. The strand n^3 of the needle thread loop is now placed positively across the face of the needle in rear thereof, while the strand n^4 has been positively placed across the face of the needle in front thereof. In Figure 13, the needle has continued its downward movement, while the looper remained at rest in the position shown in Figure 12. The needle has thus passed down into the needle thread loop which was positively laid about the needle by this reverse rotation of the looper. After the needle is well into this needle thread loop, then the looper is retracted by its rearward oscillation from the needle thread loop, and the stitch has been completed.

It will be apparent from the description given above that it is immaterial in which direction the fabric is fed. The feed of the fabric does not in any way aid in the placing of the needle thread loop for the needle to enter the same. The needle thread loop is placed on the needle by this reverse rotation of the looper. The looper in its rotation, is the sole active member in positively placing the needle thread loop carried by the looper on the needle.

Having thus described the invention, what I claim as new and desire to secure by Letters-Patent, is—

1. The combination of a needle, means for reciprocating the same, a non-thread carrying looper, means for moving the looper into and out of the needle thread loop, and means for moving the looper about an axis having a fixed position relative to the path of the needle and substantially parallel thereto while in the needle thread loop for positively placing the needle thread loop carried thereby on the needle.

2. The combination of a needle, means for reciprocating the same, a looper, means for oscillating the looper into and out of the needle thread loop, and means for moving the looper about an axis having a fixed position relative to the path of the needle and substantially parallel thereto while in the needle thread loop for positively placing the needle thread loop carried thereby on the needle.

3. The combination of a needle, a non-thread carrying looper cooperating therewith to form single thread chain stitches, means for reciprocating said needle and for giving a dwell thereto when the point of the needle is slightly below the upper edge of the looper, means for oscillating the looper and giving a dwell thereto while at the forward end of its stroke, and means for rotating the looper bodily about an axis substantially in line with the needle for positively placing the needle thread loop carried by the looper on the needle.

4. The combination of a needle, a looper cooperating therewith to form single thread chain stitches, means for reciprocating the needle and giving a dwell thereto when the point of the needle is well below the upper edge of the looper, means for oscillating the looper and giving a dwell thereto at the forward end of its stroke, and means for rotating said looper bodily about an axis in line with the needle through an arc of 360 degrees while the needle is above the material, and for rotating said looper in a reverse direction through an arc of 360 degrees for positively placing the strand of the needle thread loop on the looper against the face of the needle between the point and the eye thereof.

5. The combination of a work support, a presser foot, a presser bar carrying the presser foot, a needle, a needle bar carrying the needle, a non-thread carrying looper cooperating with the needle to form single thread chain stitches, means for oscillating said looper for moving the same into and out of the needle thread loops, means for moving the looper about an axis having a fixed position relative to the path of the needle and substantially parallel thereto while in the needle thread loop for positively placing the strands of the needle thread loop on the looper around the needle, and means operated by the needle bar for lifting the presser foot to permit the free movement of the material in any direction.

6. The combination of a work support, a presser foot, a presser bar carrying the presser foot, a needle, a needle bar carrying the needle, a non-thread carrying looper cooperating with the needle to form single thread chain stitches, means for reciprocating the needle and giving a dwell thereto when the point of the needle is just below the upper edge of the looper, means for oscillating the looper and giving a dwell thereto at the forward end of its stroke, means for rotating the looper in one direction bodily about an axis in line with the needle while the needle is on its up-stroke, and for rotating said looper in a reverse direction while the needle is at a dwell for positively placing the needle thread loop on the looper about the needle.

7. The combination of a work support, a presser foot, a presser bar carrying the presser foot, a needle, a needle bar carrying the needle, a non-thread carrying looper cooperating with the needle to form single thread chain stitches, means for reciprocating the needle and giving a dwell thereto when the point of the needle is just below the upper edge of the looper, means for oscillating the looper and giving a dwell thereto at the forward end of its stroke, means for rotating the looper in one direction bodily about an axis in line with the needle while the needle is on its up-stroke, and for rotating said looper in a reverse direction while the needle is at a dwell for positively placing the needle thread loop on the looper about the needle, and means operated by the needle bar for lifting the presser foot when the needle is at the upper end of its stroke to permit the free movement of the material in any direction.

8. The combination of a needle, a non-thread carrying looper cooperating with said needle for forming single thread chain stitches, means for reciprocating said needle and for giving a dwell thereto when the point of the needle is well below the upper edge of the looper, means for oscillating said looper, and means for rotating the looper when at the forward end of its stroke.

bodily about an axis containing the needle, including a support on which said looper is pivotally mounted, a gear for rotating said support, an oscillating segment meshing with said gear, and means for oscillating said segment, said means for oscillating the segment giving a dwell to the rotations of the looper while the looper is being oscillated into and out of the needle thread loop.

10 9. The combination of a needle, a non-thread carrying looper cooperating with said needle for forming single thread chain stitches; means for reciprocating said needle and for giving a dwell thereto when the point of the needle is well below the upper edge of the looper, means for oscillating said looper, means for rotating the looper when at the forward end of its stroke bodily about an axis containing the needle, including a support on which said looper is pivotally mounted, a gear for rotating said support, an oscillating segment meshing with said gear, means for oscillating said segment, said means for oscillating the segment giving a dwell to the rotation of the looper while the looper is being oscillated into and out of the needle thread loop, said means for
